BIDET

William H. Armstrong, Bloomfield Hills, Mich., assignor to Borg-Warner Corporation, Chicago, Ill., a corporation of Delaware

Filed Dec. 6, 1967, Ser. No. 9,660

Term of patent 14 years

(Cl. D23—51)

FIG.1

FIG.3

FIG. 1 is a perspective view of a bidet showing my new design;

FIG. 2 is a top plan view of the bidet;

FIG. 3 is a side elevation view of the bidet; and

FIG. 4 is a front elevation view of the bidet.

The dominant features of my design reside in the portions shown in full lines.

I claim:

The ornamental design for a bidet, substantially as shown and described.
